UNITED STATES PATENT OFFICE.

ARTHUR E. SMALL, OF OAK PARK, ILLINOIS, ASSIGNOR TO UNION METAL PRODUCTS COMPANY, OF CHICAGO, ILLINOIS, A CORPORATION OF DELAWARE.

DEVICE FOR OPERATING CAR COUPLERS.

Original application filed October 8, 1924, Serial No. 742,395. Divided and this application filed March 9, 1925. Serial No. 14,281.

This particular invention relates to what is generally known in the art as a rotating type of uncoupling device for car couplers and comprises an operating rod revolvably mounted on the car with brackets or in any other convenient manner, which rod is usually bent downwardly at the outer end to form a handle, and is bent outwardly at its inner end to form a crank projecting over the coupler lock lifter. The standard vertical plane coupler has a knuckle pivoted to the coupler head and provided with a tail behind which the lock is placed. The lock lifter protrudes through and above the coupler head and is provided with a horizontally positioned eye. This lock lifter eye is $1\frac{1}{16}$ " in diameter and its axis is perpendicular to the longitudinal center of the car. This size and position has been determined by the American Railroad Association and is standard for the majority of couplers now in service.

My invention resides in the connection between the crank of the operating rod and the eye of the coupler lock lifter. When the handle is raised the rod is revolved and the crank is thereby raised which unlocks the coupler by raising the lock lifter.

The coupler moves backwardly and forwardly longitudinally of the car in buffing and draft and also moves sidewise in rounding curves, etc., and the connection between the coupler and the operating rod must permit such movements without the component parts becoming disengaged from each other or from either the coupler or the operating rod. It is frequently necessary to uncouple cars when they are coupled together and in contact so that it is impossible to throw the knuckle of either coupler. To meet this condition couplers are designed to assume a "lock set position" wherein the lock lifter can be raised from behind the tail of the knuckle and retained in such a position by means within the head of the coupler independent of the operating rod. This allows the operating rod to fall close to the lock lifter. To accommodate such a movement the connection between the operating rod crank and the coupler must shorten or have a sliding engagement with either the operating rod or the coupler.

Another object is to provide a connection which may be hooked into the eye of the

coupler lock lifter with the hooked member connected to the crank of the operating rod by another member which permits it to adapt itself to the various service movements of the coupler but prevents it from becoming disengaged from the lock lifter

In the drawings:

Fig. 1 shows a portion of a railway car with my invention applied thereon.

Figs. 2 and 3 show a form of my device 65 with a non-rotative connection to the operating rod.

In a railway car the coupler operating rod 1 is mounted on the end sill 2 by brackets 3 and has a handle 4 at its outer end and a crank arm 5 extending over the coupler. The lock lifter 7 of the coupler 8 has a horizontally disposed eye 9. My invention resides in a connector for the crank arm to the lock lifter.

The connector comprises a hook member which is inserted through the eye of the lock lifter and a bar member is then threaded into it so as to close the open portion of the hook. The bar member is then non-rotatively attached to the operating rod so as to prevent it from unscrewing. The operating rod is then mounted upon the car. In certain forms the non-rotative feature is independent of the operating rod.

The longitudinal movement of the bar may be restricted by stopping the threads at such a point on the bar that it cannot be threaded into the hook further than a predetermined amount. The bar has a non-rotative attachment with the operating rod 1 which prevents it from unscrewing or backing out of the hook 31, but this attachment also preferably provides a relative sliding arrangement between the operating rod and the bar. Any non-rotative attachment between the bar and the operating rod may be used and come within the scope of this invention.

The bar 50 passes through one arm 54 of the hook 51 and has a threaded engagement 52 with the other arm 55. This gives assurance that the bar will close the open portion 53 of the hook.

This is a division of my co-pending application Serial No. 742,395, filed October 8, 1924.

I claim:

1. In a release rigging for a car coupler, the combination of an operating rod, a coupler lock lifter having an eye, a hook engaging said eye provided with two arms, and a bar passing through both of said arms having a threaded engagement with one of said arms, said bar having an operative connection with the operating rod, and means to prevent the rotation of said bar.
- 5 2. In a release rigging for a car coupler,

the combination of an operating rod, a coupler lock lifter having an eye, a hook engaging said eye provided with two arms, and a bar passing through both of said arms having a threaded engagement with one of said arms, said bar having a non-rotative engagement with the operating rod, whereby said bar and said hook are retained in proper relative relation. 15

ARTHUR E. SMALL.
